UNITED STATES PATENT OFFICE.

EDWARD J. KELLY, OF CHESTER, PENNSYLVANIA.

TANGLE ARRESTER FOR CONING MACHINES.

Application filed October 14, 1925. Serial No. 62,387.

In coning yarn for knitting machines by the usual method, the yarn comes from the spindles more or less defective by reason of loops, snarls or lumps which, in shop parlance, are designated as tangles. These tangles go to the cones and ultimately to knitting machines where they cause havoc with the needles.

The object of my invention is to provide simple and efficient means for arresting these tangles before they reach the cones.

This object, and other advantageous ends which will be described hereinafter, I attain in the following manner, reference being had 15 to the accompanying drawings in which

Figure 1 is a fragmentary end view, and

Figure 2 a fragmentary front view of a standard coning machine, showing my tangle arrester attached thereto.

Figure 3 is a perspective view of my tangle arrester.

Coning machines are well known and only such description will be given as is necessary to an understanding of my invention. Each 25 machine is adapted to wind yarn simultaneously from a plurality of spindles onto an equal number of cones but, as all the winding units are alike and for the sake of clearness, a single unit will be described as if it 30 were a complete machine.

The spindle, from which the yarn is to be wound, is placed near the bottom of the machine and the yarn led upwardly through a tensioning device, under the trigger of a tripping mechanism, over a yarn rest, and 35 onto the cone on which the yarn is to be wound. The cone rests on a winding roller which causes the cone to rotate and wind the yarn thereon.

Should the yarn break, the trigger will 40 fall and carry with it a hooked member which will engage a trip arm. This trip arm oscillates continuously so that when the hooked member drops and engages it, a 45 tripping mechanism is pulled forwardly in such a manner that the cone is raised out of contact with the winding roller, thus stopping rotation of the cone.

Referring to the drawings, 7 represents 50 a fragment of the trip arm, which is mounted on a shaft 6; 9 the tripping mechanism, to which is attached the hooked member 13 carrying the trigger 14. The winding roller 21, which is mounted on shaft 19, bears 55 against and actuates the cone 23 on which

yarn 34 is evenly wound by being led through the end of a cam driven arm 20.

My tangle arrester consists of a back 24 from which a plurality of closely adjacent pins 25 extends. The pins are arranged in 60 parallel rows and the group of pins is of rectangular outline. The pins are preferably inclined or bent uniformly so that their ends extend at an angle to the back. The back in which the pins are fixed may be carried by a flanged holder 26 having an arm 27 by which it may be adjustably connected with an arm 28 by means of a clamping member 29 and bolt 30. Arm 28 is mounted upon a pivot pin 31, extending from the 65 tripping mechanism, is made adjustable thereon by a set screw 32 and is so disposed that back 24 will be at an acute angle to the path of the yarn with the pins extending into that path and inclined in the direction from which the incoming yarn comes, as clearly shown in Figure 1. By adjusting the position of arm 28 on its pivot, the angle of the back 24 to the path of the yarn may be changed to bring a greater or less number of the ends of the pins within the area of probable contact with the tangle. By loosening bolt 30, arm 27 may be swung relatively to arm 28 and thus change the angle 70 of the transverse rows of pins 25 relatively to the path of the incoming yarn. The smaller the yarn, the greater should be this angle. Yarn guides 33 extend from the flanged member. In Figure 2, I have shown a strand of yarn 34 leading from a spindle 75 (not shown) to cone 23 and having a loop-formed tangle 35 approaching the tangle arrester. In Figure 1, I have shown loop 35 engaged with the arrester, and the yarn 80 broken.

Any tangle upon the yarn will be caught by one or more of the numerous pins. This will cause the yarn to break. Hook arm 13, which has been supported by the yarn by means of trigger 14, will then drop by gravity and engage with trip arm 7, which is oscillating continuously, thereby moving trip member 9 forwardly, thus actuating the tripping mechanism which also lifts the cone out of contact with roller 21, the mechanism being so designed that it remains in this position until reset. The tangle is then eliminated and the broken ends of the yarn connected by the operator, the trip mechanism reset and the winding may continue. 100 105 110

While I have described my invention as taking a particular form, it will be understood that the various parts may be changed without departing from the spirit thereof, 5 and hence I do not limit myself to the precise construction set forth, but consider that I am at liberty to make such changes and alterations as fairly come within the scope of the appended claims.

10 Having thus described my invention, what I claim as new and desire to secure by Letters Patent is:—

1. A tangle arrester including an arm having an aperture through one end whereby it may be adjustably mounted on a coning machine, a clamping plate removably secured to the other end of the arm, a holder clamped between the plate and the end of the arm, and a back, having a plurality of 15 pins extending therefrom, secured to the holder.

2. A tangle arrester including an arm

having an aperture through one end whereby it may be adjustably mounted on a coning machine, a clamping plate bolted to the other end of the arm, an extension having one end held between the clamping plate and the arm, a holder on the other end of the extension, a back in the holder, and a plurality of bent pins extending from the 20 back.

3. A tangle arrester including an arm having an aperture through one end whereby it may be adjustably mounted on a coning machine, a clamping plate bolted to the other end of the arm, an extension having one end held between the clamping plate and the arm, a holder on the other end of the extension, a back in the holder, a plurality of bent pins extending from the back, 25 and a yarn guide on the holder.

In testimony whereof I have signed my name to this specification.

EDWARD J. KELLY.
